UNITED STATES PATENT OFFICE.

ERNEST G. GOODWIN, OF PELHAM, NEW YORK, ASSIGNOR TO STANDARD COUPLER COMPANY, OF NEW YORK, N. Y., A CORPORATION OF NEW JERSEY.

DRAFT GEAR.

Application filed July 11, 1924. Serial No. 725,447.

This invention relates to draft gears and has for its object the provision of a substantial, self-contained draft gear of relatively high capacity and comparatively long stroke.

5 A further object of the invention is the provision in such a gear of members having non-plane faces in order to increase the frictional area and at the same time to aid in the operation of the device and also to give added 60 strength. A still further object of the invention is the provision of anchoring members for the side wedges through the medium of which it is possible to assemble and install the spring barrel with its wedges in a car 65 10 more conveniently than is possible with the average gear. Other and further objects of the invention will be apparent from the following description, and are particularly set forth in the claims.

15 20 In the drawings:—

Figure 1 is a horizontal longitudinal section of a portion of a railway draft rigging showing my improvement in connection therewith.

25 Figure 2 is a vertical section taken on the line 2—2 of Figure 1.

30 Figures 3 and 4 are sections taken on lines 3—3 and 4—4 of Figure 1, showing the contour of the contacting frictional faces respectively, of the block and center wedge and of the block and friction box.

35 Figure 5 is a perspective of a slightly modified form of outer friction wedge or block.

Figure 6 is an elevation of a modified form 40 of spring barrel friction box, of a type to cooperate with the block shown in Figure 5.

In the drawings the numeral 1 denotes the 45 two long channeled draft or center sills of the car to each of which is attached a rear stop member 2 and a front stop member 3, between which are placed the friction shock absorbing member including the front follower 4 and the spring cage or barrel with its wedges and springs, these parts being within the customary yoke 5 and supported in operative position by the saddle or supporting plate 6 detachably secured to the two center sills 1. A portion of the drawbar is shown at 7, this being connected by the usual coupler key 8 to the forward portions 9 of the yoke 5. These 50 various parts bearing numerals below 10 are illustrated merely to show the general assembly, the present invention relating entirely to the spring barrel and its wedges.

55 The spring barrel 10 is of a configuration

in cross-section best seen in Figure 2. The barrel is substantially rectangular and has strengthening ribs 11 at the sides and considerably higher ribs 12 at the top and bottom. The rear end of the barrel is entirely 60 open for the full size of the bore and ends in a rectangular flange, strengthened, in addition to the full length ribs 12, by the triangular strengthening ribs 14, between which and the central side ribs 12 there are openings 15 65 to receive rivets 16, securing in place the flat rear or end plate 17 which is permanently secured to the barrel after all of the elements of the shock-absorbing mechanism are in place.

At its front end the spring barrel 10 carries 70 a friction box 18, here shown as integral with the barrel, this being the preferred form.

The bell mouth of the friction box is preferably of the shape shown, having plane, approximately horizontal faces 19 and 20 at 75

the sides, and sloping walls 21 at the top and bottom, these top and bottom walls in the preferred construction being curved as shown in Figure 4, but the invention also contem-

plates the use of plane or substantially plane, 80 sloping friction faces, as shown in the modified box of Figure 6. In the preferred form the curved surface of the box is concave and the radius of the curve is relatively great at the center and decreases in length toward the 85

sides. The curve of each friction face merges with the plane side faces by substantial curves which make it possible to round out the 90 corners of the barrel or box, materially adding

to the strength of same, this being important, as it is intended to make the combined box and 95 barrel of cast steel and this casting, by virtue of the curving of the friction faces with the shorter radius near the corners, may be made of a thickness which corresponds closely to the strain at all points.

In both the preferred form and in the modification shown in Figure 6, the friction faces of the box are each provided with an anchoring rib 23 ending flush with the front 100 face of the friction box but terminating short of the rear edge 25 of the box, thereby forming a shoulder 26, which, when the device is expanded to full release contacts with a shoul-

der 27 forming the rear end of the groove 28 105 in the cooperating outer friction wedge or block 30. As seen in Figure 4 the friction faces 32 of the side blocks correspond exactly in their irregular curve with the curve of the

face of the friction box, and obviously these 110

curves are necessarily struck in a plane at right angles to the respective friction faces in order that there shall be the same fit of the elements at all points of travel of the gear, 6 as is quite clearly shown in Figure 4.

The center wedge 34 is generally of the well-known type except that its faces engaging the two side wedges 30 are curved. Unlike the curve of the friction box face and the 10 outer face of the side wedges, which, as shown in Figure 4 is nearly flat at the center and has its radius grow shorter and shorter towards the two sides symmetrically, the curve of the center wedge faces is constant or 15 has one radius, as shown in Figure 3, in other words the cooperating faces of the center wedge and the two side wedges are each sections of a true cylinder, this being necessary in order that the side wedges may shift 20 around the center wedge and adjust themselves to the friction box, thereby avoiding the possibility of the wedges being tight on one side and loose on the other. This configuration is also advantageous in view of the 25 fact that the spring is circular while the box is rectangular, so that the curves just described tend to equalize the thickness of all of the parts although the contour is gradually changing from a circle to a rectangle.

30 The center wedge is counterbored to receive the central spring 35 and the intermediate spring 36; the outer spring 37 engaging the center wedge 34 near its periphery, and the center wedge being enlarged upwardly 35 and downwardly, respectively, at the rear of the top and bottom in accordance with standard practice.

The provision of the anchoring means, consisting of the shoulders 26 and 27, together 40 with the separable bottom to the barrel, render the installation of the device in a car quite simple. The side wedges or friction blocks and the center wedge are placed in the box first and some small object is then placed between the contacting faces of each of the 45 anchors in such a way as to hold the gear assembled in a space slightly shorter than that into which it is to be placed. This materially simplifies the application of the gear to the car and in no way detracts from its efficient 50 operation, as the small inserts will fall away when the gear is closed the first time. Instead of inserting an entirely new piece between the retaining shoulders a small rib 38 can be cast on the shoulder of the side friction 55 block of sufficient size to resist the light static spring load but not large enough to resist shocks, soon disappearing after the gear is put into service.

60 What I claim is:

1. In a friction draft gear a spring barrel, a friction box, a block frictionally engaging said box, and a spring urged wedge frictionally engaging said block; said box and block 65 having interengaging surfaces, one of said

surfaces being concave while the other is convex, each curve having an average radius greater than the distance from the center of the gear to the outside surface of the spring barrel. 70

2. In a friction draft gear a spring barrel, a friction box, a block frictionally engaging said box, and a spring urged wedge frictionally engaging said block; said box and block having curved interchanging surfaces, 75 one of said surfaces having a rib thereon and the other surface having a groove therein receiving said rib, said rib and groove each having a shoulder, said shoulders contacting to limit relative movement. 80

3. The combination with a spring barrel for a friction draft gear, consisting of a generally rectangular casing having an entirely unrestricted open rear end and an open front end restricted by sloping friction surfaces, 85 the minimum space between which is less than the corresponding dimension of the bore of the barrel, of a plurality of wedges between said surfaces, an end plate entirely closing the rear end of said casing and secured thereto, a spring interposed between said end plate and one of said wedges, and means carried by the remaining wedges and by said surfaces for limiting the outward movement of said wedges, and temporary 90 means for still further limiting such movement. 95

4. In a device of the character described, a friction box having a plurality of inwardly converging walls, a longitudinal guiding rib 100 centrally of each wall, and terminating short of the rear edge thereof to form an anchoring shoulder.

5. In a device of the character described, a friction box having a plurality of inwardly 105 converging walls, a narrow guiding rib extending from each wall and terminating short of the rear edge thereof to form an anchoring shoulder, friction blocks cooperating therewith, each block having a groove in its 110 friction box engaging side extending from an edge of said side to a point short of the opposite edge, thereby forming a shoulder to engage the anchoring shoulder of said rib, and means for resiliently holding said blocks 115 in contact with said box.

6. In a device of the character described, a friction box having a plurality of inwardly converging walls, a plurality of friction blocks each contacting with one of said walls, 120 means for resiliently holding said blocks against said box and for permitting their contacting frictional faces to slide one on the other, a rib extending from one of said frictional faces and terminating in a shoulder, 125 a shoulder on the contacting frictional face adapted to engage the rib shoulder to limit relative movement of the block and box, one of said frictional faces being concave and the other face being convex. 130

7. In combination a spring barrel open at one end, a bell mouth friction box therefor, a detachable cover for said open end, sliding friction wedge members within said box, 5 means including a plurality of pairs of opposed shoulders for limiting the outward movement of said members, one shoulder of each pair moving within the bore of the barrel upon inward movement of the members 10 whereby a chock may be inserted between the opposing shoulders before the cover is attached to limit temporarily still further the outward movement of said members, thereby to facilitate the assembly of the gear in 15 a yoke.

8. A wedge for a friction draft gear having a groove therein to receive a travel limiting rib on the cooperating wedge, and a relatively fragile rib in said groove to limit 20 still further the travel of the wedge until said fragile rib is destroyed by the shocks incident to service.

9. In a draft gear, a casing having a friction member, a spring within said casing, a 25 plurality of friction members held by the spring in engagement with each other and with the friction member of the casing, one of the friction members having a groove therein and another of said friction members 30 having a rib thereon to slide in the groove

and to limit relative travel of the members, a fragile rib on the grooved member of sufficient strength to resist the light static load of the draft gear spring but not of sufficient strength to withstand the shocks of service, 35 said fragile rib limiting still further the relative movement of said friction members.

10. In a friction draft gear, a casing, a friction box, three cooperating wedges, one a center wedge and the other two each side 40 wedges, a spring within said casing engaging said center wedge and also the wall of the casing distant from the friction box, the engaging faces of the center wedge and the two side wedges being cylindrical, and engaging faces of the side wedges of the friction box being curved. 45

11. In a friction draft gear, a barrel having a substantially rectangular main portion, a cylindrical spring, a friction box, a center 50 wedge, a plurality of side wedges, the interengaging faces of the center and side wedges being smoothly arcuate and the interengaging faces of the side wedges and of the box being curved irregularly, the radius of the 55 curve being greatest at the center and growing less toward each side.

In testimony whereof I affix my signature.

ERNEST G. GOODWIN.
